UNITED STATES PATENT OFFICE.

GEORGE ALLEN, JR., OF NEW YORK, N. Y., ASSIGNOR TO GEORGE ALLEN & SON, A FIRM CONSISTING OF JANE ALLEN, WILLIAM ALLEN, AND GEORGE ALLEN, JR., ALL OF NEW YORK, N. Y.

CORBEL BLOCK.

Application filed June 16, 1927. Serial No. 199,161.

My invention relates to improvements in corbel blocks such as adapted for use in a masonry wall to span a part of an opening in a wall, and particularly to be included in 5 the vertical part of the wall and extend over and abut with another member or part. Such a structure is particularly useful in the construction of boiler settings and the corbel block in such structures is intended to be set 10 in the wall of the boiler setting and arch over and abut with the steam drum of a certain type of boiler. The invention is intended to lessen the cost of making a wall in which the part of an arch is used, and to produce 15 a better structure than that generally employed. In carrying out this idea I would make the block of refractory material with the inner side arched, and with the top and back generally flat, but with steps connecting 20 the flat top and flat back, the steps being of a height corresponding to the brick courses of the adjacent wall. The flat back is also of a height representing a multiple of brick courses and thus the block as a whole can 25 be conveniently set in a wall, a firm bond made with the adjacent brick courses and the inner part arching against the boiler drum or analogous member so as to effect a closure of the wall against said member and proper 30 spacing, while the top of the block forms a support for a brick or other arch which can extend over the drum or the like. This construction and the advantage of its use will be better understood and appreciated 35 from the description which follows.

Reference is to be had to the accompanying drawings in which similar reference characters represent the corresponding parts in all views.

40 Figure 1 is a side elevation of the corbel block embodying my invention showing its application to a wall of a steam boiler, and

Figure 2 is an enlarged perspective view of the block.

45 The block 10 is made of refractory material, for example fire clay, and it has its inner side curved as shown at 11, a flat top 12, a flat back 14 which is preferably perpendicular to the top 12, and steps 13 connecting the top 50 and back, these steps forming the outer and upper corner portion of the block. In Figure 1 I have shown how the block is most generally used in the wall of a boiler setting and as here illustrated, it spans the space

between the upper part of the wall and the 55 steam drum 15. It will be noted that the bottom of the block rests on solid masonry of the wall, that the back 14 of the block corresponds in height to that of several courses of masonry and that the steps 13 are 60 each of height of the commercial bricks forming the masonry courses. Thus the block can be very expeditiously and therefore inexpensively laid in the wall and it will make a 65 neat and efficient span or semi-arch connecting the wall with the steam drum 15. The brick courses can be laid without cutting or shaping the bricks so as to make a perfect bond with the back wall of the block and it is bound in so that this bond taken in connection with the fact that the inner end of the block abuts with the drum 15, a firm base is made for the brick arch 16 which can be 70 laid over the drum. The provision of the steps 13 serves to stagger the brick courses 75 and make them offset with respect to each other, so that there is no vertical straight joint common to the various courses. This is a distinct advantage obtained by the use of steps, because where a vertical straight joint is used, the cementing material therein cracks very easily under the application 80 of heat in service. By the elimination of a straight vertical joint, common to the various courses of brick, the tendency of cracking 85 is greatly reduced.

Obviously the drum 15 can be any other member with which the block 10 is to connect, and it can be used with the advantage already pointed out. In Figure 2, the dotted lines show how the brick courses fit into the steps 13 of the block so as to make a firm bond between the block and the said brick courses. In practice, the inner end of the block 10 can be trimmed if desired to make it fit and on the other hand, it can be stepped out slightly from the wall at its underpart in a manner well understood by brick masons, so as to make it span slightly more than the distance between the normal wall front and the member 15. The block can be made of any width and in laying a wall of the particular character described, it affords great economy and it produces a better structure than is usually made.

100 As shown clearly in Figure 1, the steps are 105 symmetrically arranged across the corner of the intersection of the planes of the top and

back surfaces of the block with the result that the block is reversible and either flat end may be used as the bottom. The steps further impart a substantially uniform thickness 5 to the block, the thickness varying, of course, to some extent, but being substantially uniform and within the range such that the resistance to cracking under weight and heat is substantially maximum throughout 10 the block. The resistance to cracking due to the weight supported by the block is a direct function of the thickness of the block, whereas as the resistance to cracking due to heat is practically an inverse function of the thickness 15 of the block, because the greater the thickness of the material the greater is the tendency to crack under high temperature conditions to which the block is subjected. Thus, the steps in addition to imparting reversibility to the block and eliminating the vertical straight joint, provide a block which is substantially uniform in thickness and possesses substantially maximum resistance to cracking throughout.

25 I claim:

1. A corbel block of the kind described having a flat back surface and a flat top surface disposed substantially perpendicular to each other, a plurality of steps arranged diagonal-

ly across the corner of the intersection of the 30 planes of the surfaces, said steps acting to support brick courses in offset relation and eliminate straight vertical joints extending through said courses, flat ends for the block arranged substantially perpendicular to each 35 other, said steps being disposed symmetrically so that either end of the block may serve as the bottom, and a substantially quadrantal underside connecting said ends.

2. A corbel block of the kind described 40 having a flat back surface and a flat top surface disposed substantially perpendicular to each other, a plurality of steps symmetrically arranged across the corner of the intersection of the planes of the surfaces, flat ends for the 45 block disposed substantially perpendicular to each other, and a substantially quadrantal underside connecting said ends, the thickness of the block being substantially uniform throughout and within a range such that substantially maximum resistance to cracking 50 under heat and weight is present throughout the block.

In testimony whereof, I have signed my name to this specification this 10th day of 55 June, 1927.

GEORGE ALLEN, JR.
